[57] CLAIM

The ornamental design for a golf swing guide, as shown and described.

DESCRIPTION

FIG. 1 is a perspective view of a golf swing guide showing my new design;
FIG. 2 is a front elevation view thereof;
FIG. 3 is a left side view thereof;
FIG. 4 is a rear elevation view thereof;
FIG. 5 is a right side elevation view thereof;
FIG. 6 is a top plan view thereof; and,
FIG. 7 is a bottom view thereof.

The broken line showing of the golfer in FIG. 1 is for illustrative purposes only and forms no part of the claimed design.
